UNITED STATES PATENT OFFICE.

ELMER U. AMES, OF PHILADELPHIA, PENNSYLVANIA. ASSIGNOR TO H. BRINTON COMPANY, OF PHILADELPHIA, PENNSYLVANIA, A CORPORATION OF PENNSYLVANIA.

KNITTING-MACHINE.

1,359,307.

Specification of Letters Patent. Patented Nov. 16, 1920.

Application filed February 9, 1915. Serial No. 7,111.

To all whom it may concern:

Be it known that I, ELMER U. AMES, a citizen of the United States, residing in Philadelphia, Pennsylvania, have invented 5 certain Knitting-Machines, of which the following is a specification.

My invention consists of improvements in knitting machines and is particularly designed for producing seamless tubular 10 knitted fabrics such as socks and stockings.

One object of the invention is to provide a durable practically noiseless machine of comparatively simple construction which will perform its work with a minimum of 15 attention from the operator, it being also desired to so make certain of the parts that they may be easily and accurately adjusted to effect a change in the character of the fabric made or to compensate for their wear.

20 A further object of the invention is to provide a knitting machine with mechanism which will produce a change in the size of the stitches at predetermined portions of the fabric so that a reinforcing thread may be 25 interknit therewith, the invention contemplating an arrangement of parts whereby changes in the character of fabric may be produced without unduly straining or otherwise injuring the yarn.

30 The above objects and other advantageous ends I attain as hereinafter set forth, reference being had to the accompanying drawings, in which,

Figures 1 and 2 are respectively front and 35 side elevations of a circular stocking-knitting machine made in accordance with my invention;

Figs. 3 and 4 are a side elevation and a plan on an enlarged scale illustrating certain parts of the machine shown in Figs. 1 and 2;

Fig. 5 is a sectional elevation taken on the line *a—a*, Fig. 4;

Figs. 6 and 7 are developed elevations 45 showing certain needle and sinker cams respectively in positions occupied during the making of the heel or toe of a stocking;

Figs. 8 and 9 are enlarged fragmentary elevations further illustrating the operation 50 of certain of the knitting elements;

Figs. 10 and 11 are sections respectively taken on the lines *f—f*, Fig. 8 and *g—g*, Fig. 9;

Figs. 12 and 13 are plans showing the

needles and sinkers respectively in the positions shown in Figs. 8 and 9;

Fig. 14 is a diagrammatic view showing a development of a modified form of the sinker cam which may be used in connection with my invention.

In the above drawings, 1 is a frame supporting a needle cylinder 2 which, during the operation of the machine, alternately receives a rotary and an oscillatory movement from suitable driving mechanism 12 65 and is of any suitable construction having grooves 3 for the reception of needles 4.

The upper portion of the needle cylinder has fixed to it a sinker ring 13 for the reception of sinkers or web holders 15 which 70 are normally held in definite positions relatively thereto by means of a coil spring 16 and have their ends 14 pivoted in a groove 2^a in said cylinder. The actuating arms 17 of the sinkers extend within a sinker cam 75 ring 18 surrounding the sinker ring 13 and a sinker cam 19 is mounted on said ring so as to engage the upper portions of said arms. The actuating surface of this cam is such (see Figs. 6 and 7) that when in one position, its end 19^b will depress the arms 17, causing the sinkers to assume a wave formation and to be retracted from the needles. On the other hand, when said sinker cam 19 is moved into the position shown in Fig. 7, 80 the sinkers will be depressed by the end 19^a of said cam, whose central surface 19^c is substantially plane so that when either end of the cam is moved into engagement with the end portions 17 of the sinkers to form 85 an abrupt angular part of the wave thereof, said surface will cause a gradual angular depression of the sinkers engaging it. This feature forms a very important part of my invention and will be again referred to in 90 the operation of the machine.

The cam 19 is connected to the sinker cam ring 18 by a pivot pin 20 and has a depending arm 21 extending between two screws 22 and 23 adjustable in lugs 24 and 25. These project from a sleeve 26 secured to a vertical post 27 so that when the cylinder 2 rotates in one direction, the sinkers turn with it and the friction between them, the sinker cam ring, and the needle cylinder 105 will move said ring in the same direction until the arm 21 engages one of the adjusting screws 22 or 23. Thereafter the sinker cam

- will continue to move for a short distance which will cause it to be rocked, for example, into the position shown in Fig. 3, when it will be stopped. In view of the fact that the adjusting screws and lugs are stationary relatively to the needle cylinder, the sinker arms as they pass underneath the sinker cams will cause the sinkers to form a continuous wave.
- 16 On the other hand, when the needle cylinder is rotated in the opposite direction, the sinker cam will also move with it until the arm 21 contacts with the other adjusting screw, and the continued movement of 15 the sinker cam in the same direction will cause it to rock into the position as shown in Fig. 7; it being obvious that when the needle cylinder is given an oscillating movement, as when the toe or heel of a 20 stocking is being made, the sinker cam 19 will be rocked as just described.
- The lower end of the post 27 is vertically 25 slideable within a guideway 28 (Fig. 5) formed in the frame 1, having an annular flange 29 constituting a pocket for one end of a coiled spring 30 whose opposite end engages said frame and which serves to move the post 27 upwardly after it has been depressed. The lower end of the post 27 30 is connected through a link 31 and a rod 31^a to an arm 32 of a bell crank lever 33, which is pivotally mounted on a shaft 34 mounted in suitable bearings in the frame 1. The second arm 35 of this lever is placed to be 35 actuated by a series of cams of which one is shown at 36 (Fig. 4) on a main cam drum 37 to lower the post 27 and with it the cam ring 63 during the knitting of certain portions of a stocking.
- 40 A latch ring 38 is pivotally mounted at 39 on the upper forked end 27^a of the post 27 and normally occupies a position directly over the needle cylinder so that the needles when moved upwardly will pass within it.
- 45 Said ring is prevented from swinging too far down by a bolt 40 (Fig. 3) which extends through a lug 41 thereon and has its inner end in contact with said forked end 27^a of the post. This bolt 40 also serves 50 as means for adjusting the latch ring, since by turning it the latter may be raised or lowered.
- The latch ring is entered by an opening or throat serving as a guideway for yarn- 55 guide actuating jacks 42 which are slideable toward and from the needles. In order to hold these jacks in place while permitting their limited longitudinal movement I provide two pins 46 and 47 which extend 60 through slots 44 and 45 in each of them. Yarn guide fingers 48^a, 48^b, 48^c and 48^d are pivotally mounted on a shaft 49 and each has an actuating arm 50 fitting within a 65 notch 51 in one of the jacks 42, so that a sliding movement of one of the latter will raise or lower its particular yarn guide finger within the latch ring 38. For the purpose of actuating the jacks I provide a number of bell crank levers 52^a, 52^b, 52^c and 52^d, movably mounted on a shaft 53 70 carried in an extension 54 of the frame 1. Each of these levers has an arm 55 provided with an adjusting nut 56 whose lower end is placed to engage a flat buffer spring 57 also projecting from said arm, and the 75 main drum 37 has cams 58 placed to engage these springs at certain times during the operation of the machine, so as to move the levers into the position occupied by the lever 52^a in Fig. 5. In addition to the above, 80 I also provide a yarn guide 48, designed to feed a reinforcing yarn to the needles while the others of the yarn guides are actuated by cams on the pattern drum to insert the yarns required in knitting a stocking. For 85 example the finger 48^c may be used to supply the main or regular yarn for knitting the body portion of the foot of a stocking while the fingers 48^a, 48^b and 48^d may be employed to feed splicing threads or 90 threads of different kinds, sizes or colors.
- Each jack 42 at the lower part of its rear end has a projection 42^a placed below the pivotal support 39 of the latch ring and coiled tension springs 59 serve to press said 95 jacks toward their actuating levers; one end of each spring being attached to a pin 60 on the plate 43 while its other end is attached to a depending pin 61 on one of the jacks 42.
- When the latch ring 38 is in its operative 100 position (Fig. 5) and the lever 52^a has been moved to engage and slide the jack 42 into its extreme forward position, the yarn guide 48^c is thrown up out of action. If 105 on the other hand the cam 58 on the pattern drum 37 is moved from under the lever 55, the spring 59 will move said jack 42 rearwardly and permit the yarn guide to move downwardly into a position where it can 110 feed yarn to the needles.
- While the sinkers or web holders 15 are pivotally mounted in the sinker ring 13 and normally coöperate with the needles to produce stitches in the usual manner, under 115 certain conditions, they operate to increase the size of the knitted loops. As the needle cylinder rotates and thus successively moves the ends 17 of the sinkers against the sinker cam surface 19^a so as to cause the portions of said sinkers which extend between the needles to be projected in wave form toward the axis of the cylinder, the yarn is moved into engagement with the needles and is formed into loops between the same. 120 It will be noted that when the sinker cam 19 is in the position shown in Fig. 7, the sinkers engaged by its portion 19^b will have their yarn-engaging ends farther out of mesh with the needles than any of the other 125 130

sinkers in order to form the usual sinker wave while the needles which are passing under the lowest point of the stitch cam 65 are in their lowest position and consequently have finished drawing their loops. These latter needles are in advance of the sinkers which are being acted on by the portion 19^b of the sinker cam 19 by an amount equal to the distance between the two dot-and-dash lines in Fig. 7. By having the sinker cam 10 of the construction just described, the sinkers engaged by its portion between the points 19^a and 19^b, will have a gradual movement outwardly from the axis of the needle cylinder (Fig. 6) and will again move inwardly after they have passed the point 19^b thus allowing the needles which are moving downwardly against the stitch cam 65 to hook the yarn in the ordinary manner and gradually increase the length of the loops formed until they have reached the lower portion of said cam. Obviously any change in the amount of intermesh between the sinkers and those needles which are being moved downwardly by this stitch cam 15 will vary the amount of yarn which is supplied to and can be freely taken by said needles, and will consequently vary the size of 20 the loops of the fabric which is produced.

25 From the above it will be understood that I provide mechanism hereinafter described for automatically causing the sinker ring to oscillate during the knitting of the circular tubular portions of a stocking such as the foot portion between the heel and toe, and by moving said ring as just described, the "sinker wave" is moved relatively to the needle-actuating cams and to the needles controlled thereby with the result that different amounts of yarn are pushed between 30 the needles at different times. The sinker 35 ring 48 serves as a reinforcing yarn guide, being pivoted at 133 to the upper portion of the latch ring 38 and tending to move into position (indicated in dotted lines in Fig. 8) to feed yarn to the needles under the action of a torsion spring 134 mounted within a cylindrical casing 135. Said guide 48 may 40 be moved into an inoperative or raised position by means of a jack 42^b slidably mounted like the jacks 42 and actuated by a lever 52 which may be shifted as described in connection with the levers 52^a and 52^c inclusive. Said jack 42^b may be moved away from the 45 yarn guide 48 to permit the torsion spring 134 to lower the thread guide into operative position by means of a tension spring 59^a which has one end connected to said jack and the other attached to a fixed portion of the latch ring. For controlling this movement of the parts I provide a cam 52^c in the pattern drum 31 which acts on an arm 52^e of the lever 52 to move the jack 42^b into engagement with the yarn guide 48 which is

thereafter swung upwardly and out of action.

For the purpose of making one part of a fabric with longer stitches than another part and interknitting a reinforcing yarn in the long stitch portion, the following mechanism is provided. The arm 52^a of the lever 52 is connected by a link 136 to one arm 137 of a lever 138 pivoted to a depending lug 139 on the frame 1. The other arm 140 of said lever 138 is provided with an anti-friction roller 141 which, when the arm 52^a is disengaged from the cam 52^c on the drum 31, may be engaged by a cam 142 on the under portion of the needle cylinder (Fig. 3). If it is desired that the mechanism shall 5 knit a stocking with its sole portion reinforced as above indicated, the length of this cam 142 is proportionate to the number of needles to which it is desired to feed the reinforcing yarn; it being obvious that at a 10 definite point in the rotation of the needle cylinder, the cam 142 will move the arm 140 downwardly thereby moving the reinforcing yarn guide 48 upwardly away from the needles and preventing it from feeding reinforcing yarn to the needles which knit the upper or instep portion of the foot. On the other hand, as the cam 142 passes out of engagement with the roller 141, the arm 140 will be raised by the movement of the jack 42^b under the action of the spring 59^a transmitted through the lever 52 and link 136, and said yarn guide will be moved into its lower or operative position to feed the reinforcing yarn to the needles which knit the sole part of the foot. The cam 142 and the spring 134 will thus act during each revolution of the needle cylinder to move the yarn guide 48 out of and into operative position with regard to the needles, it being understood that if the cam 142 has an angular length of 180 degrees the reinforcing yarn guide 48 will remain in operative position to feed reinforcing yarn to one-half the needles in the cylinder and will be moved into an inoperative position in which it will hold the reinforcing yarn from the remainder of the needles in the cylinder. If therefore during the knitting of the foot portion of a stocking the reinforcing yarn guide is alternately moved into and out of operative position at such times that reinforcing yarn is fed to but one-half of the needles in the needle cylinder, one-half of the knitted web will be reinforced as is desired in the sole portion of the foot. Prior to my invention it has been found difficult to reinforce the under portion of the foot of a seamless stocking without making the loops of the upper portion unduly large, especially in view of the fact that one part of each course is included in the sole portion of the foot while the remainder goes to make the upper

portion of the foot. With my invention I am enabled to knit a seamless tubular fabric such as a stocking foot in which one portion of the circumference is of short stitches while another portion is of longer stitches and includes an interknit reinforcing thread. In order that the loops of the sole portion of the stocking shall be larger than those of the upper or instep portion so that the reinforcing yarn may be interknit with the body or main yarn forming said sole portion without subjecting the needles to abnormal stress and unduly straining the loops of the several yarns as would otherwise be the case if the reinforcing yarn was knitted in a tubular foot portion made entirely of short loops, I provide the following mechanism. On the sinker cam ring is formed a lug 148 placed to be engaged by an adjusting screw 147 mounted in the end of an arm 146 of a lever 144 fulcrumed on a lug 143 depending from the lower surface of the bed portion of the frame 1. The second arm of this lever carries an antifriction roller 145 placed to be engaged by the cam 142 with which it is held in engagement and toward which it is moved by a spring 149. The arrangement is such that as the cam is moved during the rotation of the cylinder, the lever arm 146 will receive a movement toward and from the lug 148 on the sinker cam ring 18, and thereby so move said ring as to shift the position of the sinker cam 19 with a resulting alteration in the length of the loops formed.

The movement of the pattern drum 37 is such that when the foot portion of the stocking is to be knitted, the cam 52° will pass out of engagement with the arm 52° of the lever 52 which will be moved in the direction of the arrow α Fig. 3, by the spring 59°, thereby causing the jack 42° to move outwardly. This action frees the yarn guide 48 so that its movement into and out of operative position may be effected by the cam 142. By the rotation of the needle cylinder during the knitting of the foot portion of a stocking, the roller 141 is moved down by the cam 142, causing the yarn guide 48 to be moved out of operative position for a certain time during each revolution though not for such a distance as that caused by the cam 52° on the drum 37. In any case however the outward movements of said yarn guide 48 are sufficient to prevent it from feeding yarn to the needles.

In Fig. 3 the cam 142 is shown as having moved the roller 141 downwardly so that the yarn guide 48 is in its inoperative position, while the roller 145 on the lever 144 is shown in engagement with the active surface of the cam 142 with the tension spring 149 stretched. The sinker cam ring is therefore free to assume its normal position with its lug 148 in engagement with the screw 147

of the lever arm 146 as required for knitting a tubular fabric with loops of the same size throughout each course. If it be assumed that the needle cylinder is rotating in the direction indicated by the arrow γ Fig. 4, as would be required for knitting the tubular portion of a stocking foot, that the sinker cam 19 is in engagement with the adjusting screw 22 and the lug 148 on the sinker cam ring 18 is in engagement with the end of the adjusting screw 147 on the arm 146, said sinker cam and the stitch cam 65 will be in the relative positions shown diagrammatically in Fig. 7, that is to say, the sinkers and needles will be acting in the ordinary manner to produce a tubular fabric having loops of uniform size throughout its circumference. As soon as the cam 142 passes out of engagement with the roller 145, the spring 149 moves the arm 146 and thereby causes the screw 147 to move the sinker cam ring 18 through the lug 148, in a direction opposite to that of the rotation of the needle cylinder. This movement of the sinker cam ring will move the sinker cam relatively to the stitch cam 65 and thereby cause the sinkers immediately adjacent those needles passing under the lower portion of the said stitch cam, to push a greater amount of yarn between said needles and thereby effect the knitting of a long loop fabric. When the cam 142 again engages the roller 145, the latter will be moved downwardly and the arm 146 will be actuated to move the adjusting screw 147 away from the lug 148 as a result of which the friction between the sinker ring and the sinker cam ring will move the latter in the direction in which the cylinder is rotated. The sinker cam is thus caused to resume its normal position in which it causes knitting of short loop fabric, it being noted that by reason of the cam 142 extending part-way around the cylinder, the sinker cam ring and the sinker cam are alternately moved in opposite directions during each rotation of said cylinder, thus producing a tubular fabric having one part of its circumference made up of short loop fabric and the other part made of long loop fabric as previously described. Figs. 8, 10 and 12 are enlarged fragmentary views of certain of the knitting elements when the sinker and stitch cams 19 and 65 are in the normal positions in which they knit the comparatively short loop fabric, while Figs. 9, 11 and 13 show the same elements in the positions which they occupy when the sinker cam ring is moved by the action of the spring 149 as just described.

The guide 48 is so timed as to feed a reinforcing yarn to the needles which are knitting the long loop fabric and as shown in Fig. 3 it is in an inoperative position because of the roller 141 being in engagement with the active surface of the cam 142. Fig. 126

- ther, the roller 145 is in engagement with the same surface of the cam 142 and the sinker cam ring 18 and sinker cam 19 are in the position to knit said short loop fabric.
- 5 To effect the interknitting of the reinforcing yarn at the same time as the long loop fabric is being produced, the cylinder 2 rotates in the direction of the arrow y' , causing the cam 142 to pass out of engagement with the roller 141 and allowing the spring 134 to move the reinforcing yarn guide into operative position to feed the reinforcing yarn to the needles. Immediately after said guide is so moved the cam 142 will pass out of engagement with the roller 145 and allows the spring 149 to shift the sinker cam ring through the arm 146 and screw 147 in a direction opposite to that in which the needle cylinder is moving to effect the knitting 20 of the long loop fabric. It is noted that the main and reinforcing yarns are being served to the needles at the same time and that even though the loops produced are comparatively long, the fabric is of the desired compact character. Moreover, with this mechanism, a heavy reinforcing yarn may be interknit with the regular or main yarn at the sole portion of the foot without producing any undue strain on the stitches. It will 25 also be observed that as the cam 142 again engages the roller 141, the reinforcing yarn guide is returned to an inoperative position and immediately afterward the roller 145 is engaged by the said cam. The arm 46 is moved away from the lug 148, again allowing the sinker cam ring 18 to be moved by reason of its friction with the sinker ring with the result that the sinker cam and sinker cam ring return to their normal positions or to positions to knit a short loop 30 fabric during the remainder of the course.
- The roller 141 is positioned in advance of the roller 145 (Fig. 3) so that the reinforcing yarn guide 48 will move into position before the sinker cam ring 18 is moved by the spring 149, and this arrangement is made for the reason that while the reinforcing yarn is fed to the first of the needles upon which it is to be knitted when said 35 needle is on the top of the lower center cam 67 and just before it moves downwardly under the cam 65, it is not until that needle reaches the lowest portion of said stitch cam that the stitch is really formed and its 40 length is determined. Consequently the proper time for the stitch to be loosened is when said needle reaches the lower portion of said stitch cam or when it is at a point adjacent the lowest portion of said cam. In 45 Figs. 8, 10 and 12 which show the sinker cam 19 and needle adjusting stitch cam 64 in the positions occupied when the sinker cam ring 18 is in its normal position for knitting the ordinary tubular fabric from the main yarn, the needle x , which has its

lower end directly under the lowest part of the stitch cam 64, has formed its stitch by pulling the yarn to the lowest possible position. The sinkers marked A and B (see Figs. 10 and 12 particularly) do not have their thread-engaging portions A' and B' moved into their innermost possible positions; that is they are not moved in as far as the thread engaging portion C' of a sinker C.

In Figs. 9, 11 and 13, which show the same elements in the positions occupied after the sinker cam ring has been moved by the spring 149 as previously described, the sinkers A and B adjacent opposite sides of the needle x , have been moved farther in mesh with the said needle than before said cam ring was moved by the spring 149; so that this needle x which is at its lowest portion on the cam 64 is caused to knit a longer loop than when the sinker cam ring 18 is in its normal position. Consequently as each of the needles reaches the position of the needle x , it forms longer loops when the sinker cam ring is moved by the spring 149. It is to be noted that the yarn-engaging edges of the sinkers, as shown in Figs. 10 and 11, have a slight rise so that as they are pushed farther into mesh with the needles they cause the latter to pull longer loops and hence while loops of increased length may be made by the movement of the sinker cam ring, they may be made still longer by the employment of specially formed sinkers having yarn-engaging edges formed with a slight rise at points adjacent their thicke

While I have described the movement of the sinker cam ring and swinging sinker cam 19 in connection with the mechanism for moving the said ring to produce a longer stitch fabric at one part of a tube than at the other part, it will be understood that any of the well known types of sinker cams may be substituted for this cam 19 without departing from my invention as, for example, a straight sinker cam 152 (Fig. 14) which may be secured to the sinker cam ring 118. If such a sinker cam is used, the position of the sinker wave will be changed relatively to the stitch cam 65 when the cam ring is moved by the spring 119 as previously described in connection with the sinker cam 19, this swinging cam being preferable where it is desired to secure a gradual outward movement of the yarn-engaging portions of the sinkers so as to reduce the friction on the sinkers and thereby lessen the noise caused by the sinker cams during the oscillating movement of the machine.

In order to knit a long loop reinforced sole portion in the foot of the stocking, the cam 52 is so placed upon the pattern drum 37 that when the machine starts to knit said portion, it will move from under the arm

53° and the reinforcing yarn finger 48 will then be moved into an operative position to feed the reinforcing yarn; it being noted that for each revolution of the needle cylinder 2 the cam 142 will move the lever 140 and thereby cause a movement of the yarn guide 48 into and out of its yarn feeding position. Simultaneously with this action, the sinker cam ring 18 receives an oscillating movement to effect the lengthening of the stitches in the sole part of the foot in order to provide the required room for the said reinforcing yarn, and such movement is caused, as previously described, by the 15 spring 149 and by the cam 142 co-operating with the antifriction roller 145 respectively.

While I have described and illustrated mechanisms in which the sinker cam ring is moved in a direction opposite to that of the rotation of the needle cylinder for producing a fabric having longer stitches in the sole portion of the foot than in the instep portion, it is obvious that this same mechanism may be used wherever it is desired to knit one portion of the circumference of a tubular fabric with stitches of one length and another portion thereof with stitches of another length. For example a high spliced or reinforced portion above the 30 heel may be included in the lower part of the tubular leg portion by having the machine so arranged as to cause the sinker cam ring to oscillate during the knitting of the said part of the leg portion and at the same 35 time actuating the reinforcing yarn finger 48 to cause the reinforcing yarn to be interknit at the back of said portion. In such case the loops of the back may be made larger than those of the forward part of 40 the leg portion and the reinforcing yarn which forms the heel may be knit upon the needles forming the long stitch part of the leg, or if desired the reinforced yarn may be omitted.

45 While I have described a certain definite yarn guide as feeding the reinforcing and main yarns, it will be understood that any of the yarn guides illustrated may be employed to serve either the reinforcing or the 50 main yarns.

Certain of the parts of my invention shown in the drawings and above referred to form the subject of applications for U. S. Patents filed by me under date of November 55 8, 1915, Serial Nos. 60,299 and 60,300.

I claim:—

1. The combination in a knitting machine of a series of needles; means for moving said needles to cause their yarn-engaging 60 ends to form a knitting wave; means for feeding yarn to said needles; a series of sinkers all having butts of the same length; means for moving said sinkers to cause their yarn-engaging portions to intermesh with 65 the needles of the knitting wave to form a

yarn-engaging wave for said needles; with means, operative while the machine is knitting continuously in one direction, to alter the relative positions of said sinker and needle waves while maintaining their forms 70 unchanged and thereby vary the length of the stitches at predetermined points.

2. The combination in a knitting machine of a needle cylinder; needles therein; means for supplying a main and a reinforcing yarn 75 to the needles; sinkers all having butts of the same length; a sinker actuating cam operative on said butts; means for moving the needles; means for relatively rotating said cylinder and needle moving means to 80 knit a fabric; and means for circumferentially oscillating said sinker actuating cam while the machine is knitting continuously in one direction to permit of the introduction of the reinforcing yarn. 85

3. The combination in a circular knitting machine of a needle cylinder; needles therein; means for supplying a main and a reinforcing yarn to the needles; sinkers for feeding the yarn to the needles; a sinker 90 cam ring surrounding said cylinder and sinkers; a sinker actuating cam carried by said ring; and means for oscillating the ring to move said cam relatively to the needle moving means while the machine is knitting 95 continuously in one direction to increase the length of the stitches during feeding of the reinforcing yarn.

4. The combination in a circular knitting machine of a needle cylinder; needles therein; means for supplying a main and a reinforcing yarn to the needles; sinkers all having butts of the same length; needle-moving cams; a sinker actuating cam; means for relatively rotating said needle cylinder and 100 said needle-moving cams; and means for moving said sinker actuating cam circumferentially of the cylinder to increase the length of the stitches produced during the feeding of the reinforcing yarn. 105

5. The combination in a circular knitting machine of a needle cylinder; needles therein; means for supplying a main and a reinforcing yarn to the needles; a sinker ring secured to said cylinder; sinkers in said 110 ring; a sinker cam ring in frictional engagement with said sinker ring; a cam on said ring for forming a wave in the sinkers; cams for forming a wave in said needles; means for rotating said cylinder to move 115 said needles into engagement with the needle cams; means for limiting the movement of the sinker cam ring in the direction of rotation of the needle cylinder to knit a fabric; and means for moving said ring in a 120 direction opposite to that of the cylinder to move the sinker wave relatively to the needle wave and thereby increase the length of the stitches during feeding of the reinforcing yarn. 125

6. The combination in a knitting machine of a needle cylinder; needles therein; means for supplying a main and a reinforcing yarn to the needles; a sinker ring carried by said cylinder; sinkers in said ring; cams for forming a wave in said needles; a sinker cam for forming a wave in said sinkers to cause yarn to be fed to the needles; a sinker cam ring supporting said sinker cam and moved by frictional engagement with said cylinder; means for limiting the movement of said ring by the cylinder; and means for automatically moving the ring in a direction opposite to that of said cylinder to circumferentially relatively move said sinker and needle waves to increase the length of the stitches during feeding of the reinforcing yarn. 70
7. The combination in a knitting machine of a needle cylinder; needles therein; means for supplying a main and a reinforcing yarn to the needles; sinkers for feeding yarn to the needles; a sinker cam ring; a cam on said ring for forming a wave in said sinkers; a sinker ring carried by said cylinder in frictional engagement with the sinker cam ring; cams for forming a wave in said needles; means for rotating the needle cylinder to actuate the needles and move said sinker cam ring; means for limiting the movement of the sinker cam ring; and means for moving said latter ring in a direction opposite to that of the needle cylinder to circumferentially move the sinker wave relatively to the needle wave and increase the length of the stitches during feeding of the reinforcing yarn. 75
8. The combination in a knitting machine of a needle cylinder; needles therein; sinkers for the needles; means for actuating the needles; means for feeding a main and a reinforcing yarn to the needles; a sinker cam ring; a sinker cam thereon; means for rotating the cylinder to actuate said needles and move said ring; means for limiting movement of the ring; an arm having a portion for engagement with the sinker cam ring; means for moving said arm in one direction to move the sinker cam ring in a direction opposite that of the cylinder to increase the length of the stitches during feeding of the reinforcing yarn; and means for moving the arm away from the sinker cam ring to allow the latter to be again moved by the cylinder. 80
9. The combination in a knitting machine of a needle cylinder; a sinker cam ring; means for rotating said cylinder and moving said sinker cam ring; means for limiting the movement of the ring; an arm having a portion for engagement with the sinker cam ring; means for moving said arm to move the sinker cam ring in a direction opposite to that of the needle cylinder, and a cam movable with the cylinder and operative to release said arm from the sinker cam ring to permit it to again be moved in the direction of the cylinder. 85
10. The combination in a knitting machine of a needle cylinder; a sinker cam ring movable by friction with the needle cylinder; an arm having a portion for engagement with the sinker cam ring; a spring for causing said arm to move said sinker cam ring in a direction opposite to that of the cylinder; and a cam operative to cause said arm to again permit movement of said sinker cam ring in the direction of the cylinder. 90
11. The combination in a knitting machine of a needle cylinder; a sinker cam ring movable by friction with the needle cylinder; an arm having a portion for engagement with the sinker cam ring; a spring for causing said arm to move said sinker cam ring in a direction opposite to that of the cylinder; a cam operative to move said arm to again permit movement of said sinker cam ring in the direction of the cylinder; and means for adjusting the amount of movement of the sinker cam ring by said arm. 95
12. The combination in a circular knitting machine of needles; means for rotating the needles; sinkers; a sinker controlling member; and means for oscillating said member circumferentially to alternately advance and retract the sinker wave relatively to the knitting wave to permit of the insertion of a reinforcing yarn while the sinkers and the needles are coacting to form stitches. 100
13. The combination in a circular knitting machine of needles; a cylinder for rotating the needles; sinkers all having butts of the same length; a sinker controlling member operative on said butts; and means for lengthening the stitches for a part only of the revolution of the cylinder, the same consisting of means for positively moving both the sinker controlling member and the cylinder in opposite directions. 105
14. The combination in a knitting machine of a needle support; needles therein; means for supplying yarn to the needles; sinkers; a sinker actuating cam having a central face and end faces extending at an angle thereto, said cam being so shaped that its faces are at all times in engagement with the sinkers; and means for oscillating said cam to alternately move its end faces and the adjacent portions of said central face into engagement with the sinkers to form waves therein to feed the yarn to the needles. 110
15. The combination in a knitting machine of a needle support; needles therein; means for supplying yarn to the needles; sinkers; a sinker-actuating cam having a straight central face and end faces extend- 115
- 120
- 125
- 130

- ing at an angle thereto; and means for oscillating said sinker cam to alternately move said end faces and the adjacent portions of said central face into engagement with the sinkers to form waves therein to feed the yarn to the needles.
16. The combination of needles; sinkers; a sinker cam support; a sinker cam pivoted thereon having a substantially straight cam face terminating at its ends in angular cam faces; an arm projecting from said cam; with steps placed to engage said arm for rocking the cam on its pivot.
17. The combination in a knitting machine of a needle cylinder; a needle therein; means for supplying main and reinforcing yarn to the needles; a sinker ring; sinkers in said ring; cam means for forming a wave in the needles; other cam means for forming a wave in the sinkers; a sinker cam ring; and means for automatically moving said ring to cause a relative circumferential

movement of the sinker and needle waves while maintaining their forms constant, in order to increase the lengths of the stitches during the feeding of the reinforcing yarn.

18. The combination in a circular knitting machine of needles; means for rotating the needles; sinkers; a sinker controlling member; and means for oscillating said member circumferentially to alternately advance and retract the sinker wave relatively to the knitting wave, while maintaining the forms of said waves unchanged to permit of the insertion of a reinforcing yarn while the sinkers and needles are coacting to form stitches.

In testimony whereof, I have signed my name to this specification in the presence of two subscribing witnesses.

ELMER U. AMES.
